UNITED STATES PATENT OFFICE.

ANNA C. GURSKE, OF OMAHA, NEBRASKA.

DESIGN FOR A SPONGE-HOLDER.

43,038.

Specification for Design. Patented Sept. 24, 1912.

Application filed July 31, 1912. Serial No. 712,567. Term of patent 7 years.

To all whom it may concern:

Be it known that I, ANNA C. GURSKE, a citizen of the United States, residing at Omaha, in the county of Douglas and State of Nebraska, have invented a new, original, and ornamental Design for a Sponge-Holder, of which the following is a specification, reference being had to the accompanying drawing, forming part thereof.

I claim:

The ornamental design for a sponge-holder, as shown.

In testimony whereof I have affixed my signature in presence of two witnesses.

ANNA C. GURSKE.

Witnesses:

A. F. CLARK,
HIRAM A. STURGES.
